[57] CLAIM

The ornamental design for an electronic card reader, as shown and described.

DESCRIPTION

FIG. 1 is a right end elevational view of an electronic card reader showing our new design;

FIG. 2 is a left end elevational view thereof;

FIG. 3 is an inverted perspective view wherein the right end, bottom and lower front side are disclosed;

FIG. 4 is a top, left end, upper front side perspective view thereof;

FIG. 5 is a top, left end, upper front side perspective view of a second embodiment of our design.

The undisclosed views of the second embodiment are identical to those of the first embodiment.

The rear of the housing is plain and unadorned.

FIG. 1

FIG. 2

FIG. 3

FIG. 4

FIG. 5
